Primary Examiner — Michael C Stout*Assistant Examiner* — Melvin L Davis(74) *Attorney, Agent, or Firm* — Hawaii Patent Services; Nathaniel K. Fedde; Kenton N. Fedde(57) **CLAIM**

The ornamental design for a plush pillow toy, as shown and described.

DESCRIPTION

FIG. 1 is a front, right, top perspective view of the plush pillow toy, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The dashed broken lines illustrate portions of the plush pillow toy which form no part of the claimed design.

1 Claim, 8 Drawing Sheets(56)
